(57) **CLAIM**

I claim the ornamental design for a pen press, as shown and described.

DESCRIPTION

FIG. 1 is a top perspective view of the pen press;
FIG. 2 is a bottom perspective view thereof;
FIG. 3 is a side view thereof;
FIG. 4 is a side view thereof, showing the side opposite that shown in FIG. 3;
FIG. 5 is a rear view thereof;
FIG. 6 is a front view thereof;
FIG. 7 is a top view thereof; and,
FIG. 8 is a bottom view thereof.
The broken lines form no part of the claimed design.

1 Claim, 6 Drawing Sheets
